UNITED STATES PATENT OFFICE.

GEORGE F. VOIGHT, OF SAN FRANCISCO, CALIFORNIA.

LIFTING-JACK.

1,229,550.

Specification of Letters Patent. Patented June 12, 1917.

Application filed October 9, 1916. Serial No. 124,602.

To all whom it may concern:

Be it known that I, GEORGE F. VOIGHT, a citizen of the United States, residing at San Francisco, in the county of San Francisco and State of California, have invented 5 a new and useful Lifting-Jack, of which the following is a specification.

The present invention appertains to jacks, and aims to provide a novel and improved 10 operating mechanism for jacks of the "screw" type.

It is the object of the invention to provide a jack adapted especially for jacking up the axles of automobiles, wagons, and 15 the like, although useful for many other purposes, which jack is operated by the oscillation of a handle or lever, and the reversal of movement of the screw being readily accomplished simply by shifting 20 the lever longitudinally, whereby it is not necessary to reach under the vehicle for setting any pawls or like devices when it is desired to reverse the jack.

A further object of the invention is the 25 provision of a jack having the improved features above noted, and which, at the same time is comparatively simple and inexpensive in construction, it is not apt to get out of order, and is thoroughly practical and 30 efficacious in use.

With the foregoing and other objects in view which will appear as the description proceeds, the invention resides in the combination and arrangement of parts and in 35 the details of construction hereinafter described and claimed, it being understood that changes in the precise embodiment of the invention herein disclosed can be made within the scope of what is claimed without 40 departing from the spirit of the invention.

The invention is illustrated in the accompanying drawing, wherein:—

Figure 1 is a side elevation of the improved jack, portions being broken away.

45 Figs. 2 and 3 are sectional views taken on the lines 2—2 and 3—3, respectively, of Fig. 1.

Fig. 4 is a fragmental elevation of a modification.

50 Fig. 5 is a vertical section taken on the line 5—5 of Fig. 4.

In carrying out the invention, there is provided a hollow standard 1 having a suitable base 2, and a vertically movable non- 55 rotating screw 3 is disposed within the

standard and projects from the upper end thereof. The upper end of the screw 3 is provided with an axle seat or head 4 to support the object which is raised by the jack. A nut 5 is threaded upon the screw 60 and seats upon the upper end of the standard 1 to support the screw, and said nut forms the hub of a bevel gear 6. The standard 1 is provided adjacent its upper end with an outstanding pintle 7 upon which 65 is journaled for rotation a bevel gear 8 meshing with the gear 6. The gear 8 rotates about a horizontal axis, while the gear 6 rotates about a vertical axis, and this provides convenient means for transmitting the 70 motion from the operating member or lever to the nut 5.

The gear 8 is provided with an outstanding annular rim 9 having upon its periphery the teeth or lugs 10. A lever or handle 75 11 disposed in approximate horizontal position, has a longitudinal slot 12 receiving the pintle 7, whereby the lever can be oscillated and shifted longitudinally upon the pintle. The outer side of the lever 11 80 has an elongated recess 13 adjacent the slot 12 and within which recess is disposed a washer 14 which is fitted upon the pintle 7, said washer 14 being held in place by means of a cotter pin or retaining element 15 85 engaged with the pintle. Thus, the lever 11 is held upon the pintle, and said lever holds the gear 8 in place. The pintle 7 acts as a fulcrum for the lever, as well as acting as a pinion for the gear 8, and the lever 90 has a short arm projecting to the right of the pintle 7, as seen in Fig. 1, and a long arm projecting to the left in said figure. Said long arm can be of any suitable length for providing the desired leverage or purchase. The short arm of the lever has an arcuate lip 16 spaced from the periphery of the rim 9 and provided with inwardly projecting ratchet teeth 17. The other arm of the lever 11 is provided with a lip or portion 18 opposite the lip 16 and provided with inwardly projecting ratchet teeth 19. The teeth 17 and 19 are alternately engageable with the teeth 10 when the lever 11 is shifted longitudinally of itself. 95

When it is desired to elevate the screw 3, the lever 11 is shifted longitudinally to the right, as seen in Fig. 1, so that the teeth 19 thereof engage the teeth 10 of the gear 8, and then by oscillating the lever up and 110

down, the gear 8 will be rotated step-by-step, to rotate the gear 6 in such a direction as to move the screw 3 upwardly. When the lever is moved downwardly, the teeth 19 5 catch the teeth 10 and rotate the gear 8 with the lever, and when the lever is raised, the teeth 19, move idly past the teeth 10 to get a new hold on the gear. To reverse the jack, so that the screw is lowered when the 10 lever is oscillated, the lever is shifted to the left, as seen in Fig. 1, so that the teeth 19 are moved from the teeth 10, while the teeth 17 are brought into engagement with the teeth 10. Then, when the lever is oscillated, 15 the gear 8 will be rotated in the opposite direction, due to the opposite arrangement of the teeth 17 relative to the teeth 19. It is therefore only necessary to shift the lever longitudinally, for reversing the jack, 20 and it is unnecessary to make any adjustments other than this. The jack can be reversed without the necessity of changing pawls or other devices, and it is not necessary to reach under the vehicle or object 25 which is being jacked to reverse the jack. The jack can be conveniently operated in either direction.

In the variation illustrated in Figs. 4 and 5, the outstanding rim 9' of the gear 8 has 30 external ratchet teeth 10' and internal ratchet teeth 10'', and the horizontally projecting lever 11' has a slotted portion 12' engaging the pintle 7 and held thereon by the washer 14'. The lever 11' has a portion 35 16' within the rim 9' and provided with ratchet teeth 17' coöperable with the ratchet teeth 10''. Said lever 11' has a portion 18' outside of the rim 9' and provided with ratchet teeth 19' coöperable with the ratchet 40 teeth 10'. The ratchet teeth 10' and 10'' are in reversed arrangement, which is also true of the ratchet teeth 17' and 19'. When the lever 11' is shifted longitudinally in one 45 direction, the teeth 19' are engageable with the teeth 10' for rotating the gears in one direction to raise the screw, and when the lever is shifted longitudinally in the opposite direction, the teeth 17' are engageable with the teeth 10'' for rotating the gears 50 in the opposite direction so that the screw is lowered.

When it is desired to have the lever oscillate horizontally, it is assembled with the screw 3 and nut 5 in the same manner that 55 the lever is assembled with the pintle 7 and gear 8.

Having thus described the invention, what is claimed as new is:

1. In a jack, a standard, a screw movable vertically relative thereto, a nut threaded 60 upon the screw and seating upon the standard, said nut having a gear, the standard having an outstanding pintle, a gear rotatable upon the pintle and meshing with the aforesaid gear, and a lever fulcrumed and 65 slideable longitudinally upon said pintle, the lever having portions alternately engageable with the second mentioned gear when the lever is shifted longitudinally, in order that the second mentioned gear can be 70 rotated in either direction when the lever is oscillated.

2. In a jack, a standard, a screw movable vertically relative thereto, a gear threaded 75 upon the screw and seating upon the standard, the standard having an outstanding pintle, a gear rotatable upon the pintle and meshing with the aforesaid gear, the second mentioned gear having an outstanding rim 80 provided with teeth, and a lever having a longitudinal slot engaging the pintle, the lever having teeth alternately engageable with the aforesaid teeth when the lever is shifted longitudinally, whereby the second mentioned gear can be rotated in either 85 direction by the oscillation of the lever.

3. In a jack, a hollow standard having an outstanding pintle adjacent its upper end, a screw within the standard projecting out of the upper end thereof, a nut 90 threaded upon the screw and seating upon the upper end of the standard, said nut having a bevel gear, a bevel gear rotatable upon the pintle and meshing with the aforesaid gear, the last mentioned gear having 95 an outstanding rim provided with teeth, an oscillatory lever having a slot engaging said pintle whereby the lever can be shifted longitudinally, the lever having teeth alternately engageable with the aforesaid teeth 100 when the lever is shifted longitudinally, the lever holding the first mentioned gear upon the pintle, and retaining means upon the pintle holding the lever thereon.

In testimony that I claim the foregoing 105 as my own, I have hereto affixed my signature in the presence of two witnesses.

GEORGE F. VOIGHT.
